UNITED STATES PATENT OFFICE.

SAMUEL W. BEESON, OF BUFFALO, NEW YORK.

TRACK FOR DOOR-HANGERS.

No. 896,682.

Specification of Letters Patent.

Patented Aug. 18, 1908.

Original application filed March 4, 1907, Serial No. 360,344. Divided and this application filed March 2, 1908.
Serial No. 418,639.

To all whom it may concern:

Be it known that I, SAMUEL W. BEESON, a citizen of the United States, residing at Buffalo, in the county of Erie and State of New York, have invented a new and useful Improvement in Tracks for Door-Hangers, of which the following is a specification.

This invention relates to a track which is more particularly designed for supporting door hangers of box freight cars, but the same may also be used for other purposes.

The object of this invention is to produce a track for this purpose which is simple and durable in construction, which will reliably support the hanger and the door suspended by the same, which can be produced and maintained at comparatively small cost and which is not liable to become deranged and rendered inoperative by the jarring or straining of the car.

This application is a subdivision of an application for patent filed by myself March 4, 1907, Serial No. 360,344, and patented April 8, 1908, No. 833,775.

In the accompanying drawings: Figure 1 is a fragmentary perspective view of a box freight car having its door suspended from my improved track. Fig. 2 is a fragmentary vertical transverse section taken in line 2—2, Fig. 3. Fig. 3 is a fragmentary longitudinal section in numbered line 3—3, in Fig. 2.

Similar letters of reference indicate corresponding parts throughout the several views.

Those parts of the car or other structure which receive my improved track are preferably constructed as follows:—A represents a supporting beam secured lengthwise and horizontally on the outer side of the side plate B by means of a plurality of horizontal bolts *b* passing transversely through these parts at intervals. On the underside of this supporting beam the same is provided with a longitudinal groove or seat *c* which is semi-circular or nearly so in cross section. In this groove is seated the upper side or half of a longitudinal tubular guide, way or track D which is provided on its underside with a longitudinal slot *d*. This tubular track or guide is firmly secured in the groove of the supporting beam by means of a plurality of vertical bolts *e* passing through the upper portions of the track and the supporting beam and each bearing with the head at its lower end against the bore or inner side of the track while its nut bears against the upper side of the sup-

porting beam and is prevented from becoming loose by means of a cotter pin, as shown in Figs. 2 and 3, or any other suitable means.

The horizontal bolts which connect the supporting beam with the plate B and the vertical bolts which connect the tubular track with the supporting beam are preferably so disposed that each horizontal bolt *b* is arranged close to one of the vertical bolts *e*, as shown, so that a firm connection is made between the beam and plate immediately at the point where the vertical bolts connect the beam with the track, thereby reliably connecting the track with the car body and effectually securing against warping or displacement of the same under the jars or other destructive action to which the car is subjected. The suspending device whereby the door is slidably supported from said tubular guide or track consists preferably of two hangers or shoes F. Each of these hangers consists of an upper enlargement, head or runner *f* which is adapted to slide lengthwise in the bore of the tubular track, a reduced portion or neck *g* projecting downwardly from the underside of the head through the slot in the bottom of the track, and a socket *h* which is arranged at the lower end of said neck and in which the upper edge of the adjacent portion of the door is secured by means of bolts *i* or otherwise. The upper side of the head is concaved or recessed lengthwise so as to form a clearance space *j* for avoiding interference with the heads of the vertical bolts *e* which are arranged in the upper part of the track.

Inasmuch as the tubular track is confined on opposite longitudinal sides by the walls of the groove of the supporting beam the metal of the track on opposite sides of its slot is held against spreading under the downward pull of the hanger, thereby always retaining the guiding and supporting devices of the door in their operative condition. The inner wall of the groove of the supporting beam is confined between the tubular track and the adjacent plate of the car body, whereby this wall is positively held against displacement. In order to also guard against any possibility of the outer wall of said supporting beam from becoming displaced a plurality of clips are provided each of which consists of a vertical body plate K secured to the outer side of the supporting beam by one of the horizontal bolts *b*

and a lip *l* projecting inwardly from the lower end of the plate *K* and engaging with the underside of the supporting beam along the outer side of its groove.

5 By confining the tubular track in the supporting beam in the manner described, the same is held perfectly straight at all times and prevented from becoming accidentally bent, thereby insuring a smooth surface for 10 the supporting shoe or hanger to run on and enabling the door to be easily opened and closed at all times. The lower edge of the door is prevented from swinging outwardly away from the car body by the usual door 15 track brackets *m*, but if these should be accidentally knocked off, the door would still be prevented from swinging outwardly by engagement of the outer sides of the necks of the hangers with the stationary edge of the 20 tubular track, thereby avoiding interference and damage by collision of the door with other cars or obstructions which would be liable to occur if the tubular track were not held rigidly in position.

25 I claim as my invention:

1. The combination of a horizontally disposed tubular track of circular cross section having a longitudinal slot in its underside, with a longitudinal supporting beam pro-

vided on its underside with a longitudinal 30 groove of semi-circular cross section in which the upper half of said track fits snugly, whereby the lower parts of the track on opposite sides of its slot are sustained against spreading under the weight of a door hanger resting 35 thereon, means for connecting the top of the track with the beam, and means for connecting the beam with a support.

2. The combination with an upright support and a horizontally disposed beam having 40 a groove in its under side, bolts connecting said beam and support, of a horizontally disposed tubular track having a longitudinal slot in its under side and adapted to be seated in said groove, bolts connecting said 45 track and beam, and clips each having a vertical body which is secured to the outerside of said beam by one of said horizontal bolts and a lip arranged on said body and engaging with the adjacent lower edge of said beam, 50 substantially as set forth.

Witness my hand this 26th day of February, 1908.

SAMUEL W. BEESON.
